UNITED STATES PATENT OFFICE.

MANIOUS GARL, OF AKRON, OHIO.

FIRE-ALARM SYSTEM.

1,363,246.

Specification of Letters Patent. Patented Dec. 28, 1920.

Application filed May 18, 1917. Serial No. 169,567.

To all whom it may concern:

Be it known that I, MANIOUS GARL, a citizen of the United States, residing at Akron, in the county of Summit and State of Ohio, have invented new and useful Improvements in Fire-Alarm Systems, of which the following is a specification.

The present invention relates to improvements in fire alarm and other systems which 10 employ a number of instruments adapted to transmit signals to a central or other receiving station.

One of the primary objects of the invention is to provide improved contact or circuit controlling means for such instruments which will be unaffected by gases or other influences which produce corrosion and thereby prevent proper engagement of contacts of the ordinary exposed type, in consequence of which good conductivity between the contacts is insured at all times, and certainty and reliability in the operation of the instruments are attained.

Another object of the invention is to provide a system of this character which has a normally closed line circuit which does not depend upon utilizing the earth or ground as a part of such circuit; and to provide a telephone having means for connecting it 30 in series with the line circuit and having a local battery which is connected in series with the battery or source of energy for the line circuit, injury to the system or disturbance in the operation thereof by other electric systems which commonly use the earth or ground as a part of their circuit being avoided.

A further object of the invention is to provide means whereby a break in the line circuit of the system may be quickly and easily located to enable the necessary repair to be made promptly and, pending such repair, the system will be in operative condition, using the ground temporarily as a part of its 45 circuit.

To these and other ends, the invention consists in certain improvements, and combinations and arrangements of parts, all as will be hereinafter more fully described, the 50 novel features being pointed out particularly in the claims at the end of the specification.

In the accompanying drawings:

Figure 1 is a front elevation, partly in section, of an instrument embodying the present invention, the instrument being adapted

for use in connection with a fire alarm system.

Fig. 2 is a rear elevation of the instrument shown in Fig. 1.

Fig. 3 represents a section on the line 3—3 of Fig. 2, looking in the direction of the arrow.

Fig. 4 represents a section on the line 4—4 of Fig. 1.

Fig. 5 is a bottom plan of the instrument as shown in Fig. 2.

Fig. 6 is a detail view, partly in section, showing the circuit controlling device or breaker embodying the present invention.

Fig. 7 represents a central axial section through the circuit controller or breaker.

Figs. 8 and 9 represent sections on the line 8—8 of Fig. 2, the releasing lever for the instrument being shown in two different positions in these views.

Fig. 10 is a diagram showing a fire alarm system having two instruments connected therein, the diagram also showing the telephone adapted to be connected in series in the fire alarm system; and

Figs. 11 and 12 are detail perspective views showing, respectively, the telephone jack and plug for one of the boxes or instruments.

Similar parts are designated by the same reference characters in the several views.

The present invention is applicable generally to fire alarm telegraph systems or other electric systems which comprise a number of signal-transmitting instruments and a central or other station for receiving the signals from the different instruments.

In systems of this character, and especially in fire alarm telegraph systems, it is of great importance that certainty and reliability in the transmission of the signals be insured at all times. It has been found, however, from experience, that the ordinary open or exposed contacts, such as those employed in the usual fire alarm systems, are corroded or otherwise attacked by gases, this being particularly the case with instruments installed in rubber factories and other places where the contacts are subject to the corroding influence of sulfur gases. Corrosion of the electrical contacts of the instruments prevents proper engagement or electrical conductivity between the contacts, and when that occurs, the instrument and, in some cases, the entire system, is rendered inoperative. It has also been found that where

the fire alarm system utilizes the earth or ground as a part of its operative circuit, the system is liable to damage and to interference with its operation should the line wire 5 of the system come in contact with the overhead or line wire of another electrical system, it being common in some localities to employ the earth or ground as the return part of the circuit of various electrical systems, and contact between the line wire of 10 the fire alarm system and the line wire of one of the other systems would result in the flow of electric current from the other system over the fire alarm system.

15 These difficulties are avoided by the present invention, the preferred embodiment of which is shown in the accompanying drawings and will be hereinafter described as applied to a fire alarm system. It is to be 20 understood, however, that the invention is not restricted to the precise construction and arrangement shown, as equivalent constructions are contemplated and will be included within the scope of the claims.

25 In the present instance, wherein the invention is shown applied to a fire alarm system, each instrument is preferably fitted into a suitable box 1 which may be of metal mounted on or attached to a post or pipe 2, 30 the box being preferably grounded with the post or pipe 2. A door 3 serves to close the front of the box and it may have a glass or other breakable panel 4 through which the releasing member of the instrument may be 35 reached for manipulation without the necessity of opening the door, although the door may be opened by an attendant for inspection, repair or other purposes. The instrument which is preferably mounted in the upper part of the box 1, has its parts supported 40 on a base 5 which is preferably grounded with the box, and a front plate 6 is mounted on the base plate 5. The circuit controller of the instrument comprises a disk 7 of hard 45 rubber or other insulating material which is mounted to turn with an operating shaft 8, and the disk 7 has pins or teeth 9 projecting from its periphery, the number and arrangement of the pins corresponding to the number 50 of the particular instrument. For example, the pins are grouped to represent the number 451, it being understood that the number and arrangement of the pins on the different instruments in the system will be 55 grouped in different ways so that each instrument will have its individual number. A casing 10 of suitable insulating material is secured to the front of the plate 6, the casing having a rear wall 11 which closes it, and a 60 glass 12 is adapted to close the front of the casing, this glass being removably held in place by a screw cap 13. The casing is preferably round, or substantially so, and it is provided at the bottom with partitions 14 and 15 of insulating material, these parti- 70 tions subdividing the bottom of the casing to form wells 16 and 17, and these wells contain bodies of mercury. Metallic conducting strips 18 and 19 are arranged in the bottoms of the wells 16 and 17, these strips being preferably co-extensive with the bottoms of the wells and presenting relatively large areas of contact with the bodies of mercury, thus insuring the flow of current between the strips and the bodies of mercury with a minimum resistance. A binding post or terminal 20 extends through the wall of the casing above the level of the mercury baths and is connected to the conducting strip 18. A hollow terminal 21 also extends through the wall 80 of the casing above the level of the mercury baths and is connected to the conducting strip 19. A circuit controller 22 is provided to establish and to break the circuit between the conducting strips 18 and 19. Preferably, 85 and as shown, the circuit controller is yoke-shaped, it having a pair of arms 23 and 24 which are arranged to operate in the wells 16 and 17 respectively. The circuit controller is pivoted to rock freely on a pivot pin 25, 90 gravity serving to move the arms 23 and 24 downwardly so that their lower ends normally rest on the conducting strips 18 and 19, and the intermediate portion 26 of the circuit controller is in the path of the pins 95 or projections 9 whereby rotation of the wheel or disk 7 in the direction of the arrow in Fig. 6 causes the pins to successively co-operate with the circuit controller to lift the latter into the dotted line position and clear 100 of the bodies of mercury in the baths 16 and 17, and as each pin passes the intermediate portion 26 of the circuit controller, the latter drops by gravity to the full line position where the lower ends of its arms 23 and 24 105 engage the conducting strips 18 and 19. Obviously, when the circuit controller is elevated by each pin, the circuit between the conducting strips 18 and 19 is broken, whereas when the circuit controller is in its lower 110 position, the circuit controller establishes electrical connection between the conducting strips 18 and 19. The pivot pin 25 on which the circuit controller rocks is carried by a suitable bracket 27, the latter being secured 115 within the casing 10 by a binding screw 28. In the ordinary operation of the instrument, the circuit controller is actuated by the pins 9 of the breaker wheel, but on some occasions it is desirable to manipulate the controller manually to send special signals over the system. In order to provide for such manual manipulation of the circuit controller, a plunger 29 may be employed, this plunger consisting preferably of a metallic 120 rod which extends through the hollow binding post 21 and having a button 30 on its outer end for manipulation by the finger, and the inner end of the plunger having a head 31 arranged to co-operate with the under side 125 130

of the circuit controller 22 whereby inward pressure of the plunger will manually raise the breaker sufficiently high to break the circuit between the conducting strips 18 and 19. A spring 32 serves to normally hold the plunger in inoperative position where it will not interfere with the automatic operation of the circuit controller, and an insulating bushing 33 serves to limit the outward movement of the plunger under the action of the spring 32.

The breaker wheel 7 which is rotated by the shaft 8 may be actuated by any suitable means such, for example, as the ordinary 15 clock motor. As shown, the clock motor comprises a drum 34, preferably of insulating material and mounted to turn with a shaft 35, the latter being journaled in the front plate 6 and in the rear plate 36. A 20 wire or cord 37 is wound upon the drum 34 and has an actuating weight 38 attached thereto. The shaft 35 which carries the drum 34 has a gear wheel 39 mounted loosely thereon, and this gear wheel is 25 adapted to be connected to the shaft 35 by a ratchet and pawl device 40 whereby rotation of the shaft 35 under the action of the weight 38 will cause rotation of the gear wheel 39, but rotation of the shaft 35 30 in a reverse direction which will lift the weight will be permitted by the ratchet and pawl device while the gear wheel 39 remains motionless. A cord or wire 41 which is also wound on the drum 34 serves to rotate the drum 34 in a reverse direction for 35 the purpose of raising or resetting the weight 38. The gear wheel 39 coöperates with a pinion 42, this pinion being fixed to the shaft 8 which carries the breaker wheel, 40 and by this arrangement, rotation of the gear wheel 39 under the influence of the weight 38 will cause rotation of the breaker wheel. The ratio of the gear wheel 39 and the pinion 42 may be varied, but it is generally 45 preferable to employ a ratio whereby the breaker wheel shaft 8 will revolve four times to one revolution of the shaft 35. In order to control the speed of rotation of the breaker wheel, an escapement 43 is provided, this escapement being mounted on a rock shaft 44 and coöperating with an escapement wheel 45, the latter being mounted on a shaft 46 and carrying a pinion 47 which coöperates with a gear wheel 48 on 50 the breaker wheel shaft 8. The multiplying gearing between the shaft 8 and the shaft 46 enables the vibratory escapement to retard to the proper degree the speed of rotation of the breaker wheel. A weight 49 is fixed to the escapement shaft 44 and serves to retard the vibration of the escapement.

The shaft 35, which is grounded, is connected to a disk 50 of brass or other suitable conducting material. This disk 50 is

secured to the rear face of the drum 34 and a portion 51 of its periphery is raised so as to project beyond the circumference of the drum 34, while the remaining portion 52 of its periphery is of less diameter than the drum 34 and is below the periphery thereof. A spring or brush 53 is arranged to ride upon the raised portion 51 of the disk 50 or upon the periphery of the insulating drum 34 during a revolution of the shaft 35. This spring or brush is insulated from the base plate 5 by an insulating support 54, and the spring or brush is connected by a binding post 55 and a conductor 56 to a binding post 57, the latter extending 80 through the front plate 6 to the front thereof and being connected by a conductor 58 to the binding post 28, the binding post 57 being insulated from the grounded plate 6. Under normal conditions, the weight 38 is 85 in elevated position, as shown in Figs. 2 and 3. In order to retain the weight in such position but to permit its release and cause operation of the instrument, a circumferentially grooved plug 59 is attached 90 to the weight or to the cord 37, and the base plate 5 is formed with a keyhole aperture 60. A lever 61 is also pivoted at 62 to the under side of the base plate, and this lever has an aperture 63 therein which is sufficiently large to permit the passage of the plug therethrough. When the weight is in its normal elevated position and the plug 59 is fully raised, the lever 61 occupies the full line position shown in Fig. 5 and thus 100 serves to retain the grooved portion of the plug 59 in the narrower portion of the keyhole slot 60 in the base plate 5, the weight 38 being thereby supported in its elevated position, but when the lever 61 is swung 105 into the dotted line position shown in Fig. 5, the plug 59 is moved into the larger end of the keyhole slot 60 and the plug may then pass downwardly through the plate 5 and the lever 61, and the weight 38 is then 110 free to rotate, the drum 34 thereby actuating the breaker wheel. The weight rewinding cord 41 may extend downwardly through a bushing 64 in the base plate 5 and it may be provided at its lower end 115 with a button or handle 65 by means of which it may be pulled downwardly to rewind or reset the weight after the instrument has been operated. The lever 61 is preferably provided with a handle 66 at its 120 forward end, and this handle may be arranged immediately within the glass or other panel 4 so that when the panel 4 has been broken or removed, the handle 66 may be easily reached for manipulation.

A pair of line terminal posts 67 and 68 is provided, these terminal posts being insulated from the base plate 5 by insulating bushings 69 and 70, and the post 67 is connected to a binding post 71 which is also in- 130

sulated from the base plate 5 by an insulating strip 72, the binding post 71 being connected by a conductor 73 to a binding post 74, the latter being fitted into but insulated from the front plate 6. The binding post 74 extends to the front of the plate 6 and it is connected by a conductor 75 to the terminal or binding post 21. A strip 76 of insulating material is provided on the upper side of the base plate 5, and a conductor strip 77 overlies the insulating strip 76 and is connected to the terminal post 68. The conductor strip 77 is connected to a binding post 78 which is fitted in but insulated from the front plate 6, this binding post 78 being connected by a conductor 79 to the terminal 20. Each box or instrument is provided with a telephone jack which is bridged across the line terminals 67 and 68 whereby a telephone may be introduced into the line circuit of the system, the shunt or bridge circuit of the telephone jack being open under normal conditions when the telephone is not in use. The telephone jack may be made in different ways. As shown, the conductor strip 77 provides one terminal or contact 80, and a plate 81 connected to the terminal 67 provides the coöperating terminal or contact 82, the front plate 6 being provided with a socket 83 through which the telephone plug may be inserted, and the telephone jack is in position to coöperate with the respective terminals of the telephone plug when the latter is inserted into the socket. The telephone plug may be made in different ways, although it is preferable to use a telephone plug of a type similar to that commonly used in connection with telephone systems. The plug shown in the present instance in Fig. 12 comprises a handle 84 having a conducting sleeve 85 projecting forwardly therefrom to a point near its end, an insulating bushing 86 which is fitted within the conducting sleeve, and a central or inner terminal or electrode 87, the wires 88 and 89 of the telephone being connected, respectively, to the conducting sleeve 85 and the inner terminal 87, and when the plug is inserted into its socket, the conducting sleeve 85 will contact with the terminal 82 of the jack, while the inner terminal 87 of the plug will contact with the terminal 80 of the jack. When the plug is introduced into the jack, the telephone at the box or instrument is introduced into the fire alarm system in shunt therewith. According to the present invention, a telephone is also provided for the central or receiving station, this telephone embodying the usual transmitter 90 and receiver 91 and, in addition, a local battery 92, the transmitter and battery of the telephone being connected in series with one another, and when the telephone plug 65 is inserted in the telephone jack at central

station, the local battery of the telephone will be connected in series with the battery or source of energy for the fire alarm system, thus overcoming the increased resistance offered by the telephone system and 70 the relay 105 at the central station.

The battery B' of the main circuit may at times get low or weak so that the current of the closed circuit is not much more than sufficient to keep the relay 105 energized to 75 such an extent as to maintain the armature thereof in an elevated position. Should an attempt be made to use the telephone under such conditions, without the local battery 92, the current from the battery B' 80 would not be sufficient to overcome the extra resistance introduced into the circuit and at the same time keep the relay 105 sufficiently energized. The battery 92 supplies a sufficient amount of current to overcome the extra resistance introduced into the circuit, so that there is no danger of the relay 105 being closed because the current from the battery B' is not sufficient to overcome the increased resistance of the telephone circuit and keep the relay properly energized. Furthermore, the local battery 92 is necessary for enabling the telephone to be used when the main line is broken, as at the point X in Fig. 10, and a grounded 95 circuit is utilized for the fire alarm. The switch S is then in the dotted line position indicated by Fig. 10, with the two arms thereof moved into engagement with the contact points 110 and 101. A telephone 100 circuit is then established through the wires 111 and 100, without interfering with the grounded main line circuit. The current for the telephone circuit is then supplied by the local batteries 92, and the telephone 105 would be entirely inoperative if it were not for the battery 92. This enables a lineman to communicate with the central station and instruct the operator to move the switches S and S' back to their normal positions 110 after the line has been prepared.

As shown in Fig. 10, a telephone jack J is provided at the central station which is adapted to receive a telephone plug P of the central station telephone, the jack J having 115 its terminals connected in series with the line wire 103, and a circuit closer K arranged in shunt with the jack serves to complete the line circuit when the telephone is not in use. Preferably, and as shown, a 120 spherical head 93 is provided which is adapted to enter between and to connect the terminals of the circuit closer K while the telephone plug is not in position, this head being carried on an arm 94 which latter is 125 pivoted at 95 to a suitable support 96. With this arrangement, the head 93 will normally connect the terminals of the circuit closer K, but when the telephone is used, this head 93 is disengaged from the circuit closer K after 130

the telephone plug has been inserted, the telephone being connected in series with the fire alarm system and thereby completing the circuit of such system.

5 Preferably, and as shown, a grounding key 97 is provided for a purpose that will hereinafter appear, this key comprising a spring which is secured at one end and electrically connected to the line terminal 68, 10 and its opposite end is normally adjacent to but separated from the under side of the base plate 5, upward pressure on the free end of the key, however, serving to engage it with the base plate, thereby grounding the 15 side of the system to which the terminal 68 is connected.

A fire alarm system embodying the present invention and having a plurality of instruments connected therein is shown diagrammatically in Fig. 10. In this diagram, 20 A and B designate, generally, two of the instruments of the system, C represents diagrammatically the central or receiving station, and T and T' represent diagrammatically telephones adapted to be introduced into the system at a box or instrument and at the central station, respectively. The circuit of the system, including the various instruments, is normally closed and receives 25 energy from a main battery B', one terminal of this battery being connected by a conductor 98 to one blade 99 of a double switch S. A conductor 100 leads from the contact 101 of the switch S to the box A 30 through which the circuit of the system is normally closed, and a conductor 102 leads from the box A to the box or instrument B, this conductor 102 leading to the line terminal 68, the conductor 77 leading from the 35 terminal 68 to the binding post 78, this binding post being connected by the conductor 79 to the terminal 20 of the circuit controller. The terminal 20 is connected to the conducting plate 18 submerged in the body 40 of mercury in the well 16, and the other conducting plate 19 submerged in the body of mercury in the well 17 is connected to the binding post 21. The binding post 21 is connected by the conductor 75 to the binding 45 post 74, and the latter is connected by the conductor 73 to the line terminal 67. The line wire 103 leads from the line terminal 67 to such other instruments as may be included in the system, through the circuit closer K, and it terminates at the line 50 terminal 104 of the relay 105, the latter being located at the central or receiving station. The other line terminal 106 of the relay is connected by the conductor 107 to the opposite terminal of the main battery B'. The instrument B is adapted to be connected to the ground G² through the frame or metallic parts of the instrument which is designated diagrammatically in Fig. 10 as a 55 conductor 108 which leads to the shaft 35,

the ground connection being made through the disk 50, the brush or spring contact 53, the conductor 56, binding post 57, conductor 58, and the terminal 28, the latter being electrically connected to 60 the circuit breaker 22. The instrument A is provided with a ground G' which corresponds to the ground G² of the instrument B. A main ground G is provided for the system, but this ground normally is not 65 used. To enable the system to be grounded when such is desirable, the ground conductor 109 leads to a contact 110 which is adapted to be engaged by the blade 99 of the switch S, when this switch is shifted 70 into the dotted line position shown in Fig. 10, one terminal of the battery B' being then grounded through the conductor 98. An additional conductor 111 may also be extended from the line terminal 104 of the 75 relay to the other blade 112 of the switch S, this blade of the switch being connected by the member 113 to the blade 99 whereby these blades will move in unison, and when the switch S is in its normal position, the 80 conductor 111 will not be included in the system, but when the switch S is shifted to the dotted line position in Fig. 10, the conductor 111 will be connected through the terminal 101 to the line wire 100. The local 85 terminal 114 of the relay is connected to one terminal of a local battery B², while the other local terminal 115 of the relay may be connected to the conductors 116 and 117 90 which are connected respectively to a bell 100 118 and a suitable register or indicator 119, the other terminals 120 and 121 of the bell and register respectively being connected by a conductor 122 to the other side of the local battery B². The local circuit of the 95 relay is of a type whereby the bell, register, or other indicators or instruments connected therein will be caused to act when the normally closed line circuit of the relay is 100 broken, it being understood that the line 105 circuit of the system is normally closed. The telephone at the central station, according to the present invention, is introduced in series in the line circuit of the system, and, furthermore, the polarity of the telephone 110 battery 92 is such in relation to the main battery B' of the system that the positive side of the battery 92 will be connected to the negative side of the main battery B', that is to say, the telephone battery 92 is 115 connected in series with the main battery B' whereby the telephone battery 92 will supplement the energy supplied to the system by the main battery.

In order to provide for operation of the 120 system using the ground as a return, a second relay 123 is preferably used at the central station, the main circuit terminal 124 of which is connected by a conductor 125 to the local circuit terminal 115 of the relay 125 130

105 and the other main circuit terminal 126 of which is connected to a contact 127 of a switch S', the blade 128 of this switch being connected to the conductor 122 leading from the positive side of the local battery B² of the relay 105, and the blade 129 of the switch S' is connected by a conductor 130 to the local terminal 131 of the relay 123, the other local terminal 132 of the relay 123 being connected by a conductor to the positive side of a local battery B³, and the other side of this local battery being connected to the local terminal 115 of the relay 105.

By using a second relay connected as described, the bell and register will act in the same way when the ground is used for the return of the main line system as they act when the all-metallic line is used, in view of the following mode of operation:—When the line circuit of the system is broken, the local circuit of relay 105 will be closed. By shifting the switch S' from the full line to the dotted line position (Fig. 10), the main circuit of relay 123 is introduced into the local circuit of relay 105 and the local circuit of relay 123 will then be open. Any signal or alarm coming over the system from an instrument connected therein will then cause the bell and register to operate in response to the signal just as the relay 105 would cause operation of the bell and signal in the normal condition of the system.

When the main line is broken and a grounded circuit is used for the alarm, this grounded circuit is normally an open circuit instead of a closed circuit, as in the previous instance. The grounded circuit is normally broken by reason of the fact that the contact spring 53 engages an insulated portion 40 of the disk 50. Through these conditions the relay 105 is normally closed instead of open. This would result in a continuous indication on the register 119 and a continuous sounding of the gong 118, were it not for the fact that the second relay 123 is rendered operative by the shifting of the switch S' into the dotted line position shown by Fig. 10. It will thus be seen that when the system operates upon a grounded circuit 50 the relay 105 is normally closed and the relay 123 normally open. When an alarm is sounded at any one of the stations, the rotation of the disk 50 at the particular station brings a metallic portion thereof into 55 engagement with the contact spring 53 and closes the grounded circuit so that the alarm can be turned in over the grounded circuit. In sounding the alarm the relay 105 will then be intermittently opened, instead of intermittently closed, as when the device is 60 operating on a closed circuit. However, the use of the second relay 123 causes the alarm to be sounded in exactly the same manner as with a closed circuit.

65 The operation of the system may be de-

scribed, briefly, as follows:—Normally, the switches S and S' occupy the positions shown by the full lines in Fig. 10, and hence the main battery of the system will not be grounded, and the actuating weights of the various instruments in the system will be in elevated position and retained in such position by the releasing lever 61 of each instrument. Also, the toothed wheel 7 of each instrument will occupy such a position relatively to its respective circuit breaker 22 that, upon the commencement of the rotation of the toothed wheel, the circuit breaker will begin its operation of sending an alarm or signal corresponding to the number of the particular instrument. While the instruments are inactive, as is normally the case, the circuit is normally closed throughout the system as follows:—Starting with the main battery B', the current passes over the conductor 98, the switch blade 99, conductor 100, through the instrument A, over the line conductor 102, terminal 68, conductor 77 to binding post 78, over the conductor 79 to terminal 20 to the conducting plate 18 submerged in the mercury in the well 16, thence up the arm 23 of the circuit breaker 22, thence down the arm 24 of the circuit breaker to the conducting plate 19 submerged in the mercury contained in the well 17, thence to the terminal 21, over the conductor 75 to the binding post 74, thence over the conductor 73 to the binding post 67, thence over the line conductor 103 and the circuit closer K therein to the line terminal 104 of the relay through the line circuit of the relay to the line terminal 106 of the relay, and thence by the conductor 107 to the return side of the main battery B'. In order to send a signal or alarm from any instrument, it is only necessary to break or remove the panel 4 of the particular box or instrument and then push the handle 66 of the lever 61 toward the left in Fig. 1. This operation releases the plug 59 attached to the weight cord 37 and the weight 38 then acts upon the drum 34 to rotate the shaft 35. Motion from the shaft 35 is transmitted to the shaft 8, and the toothed wheel 7 is thereby caused to revolve. During the revolving motion of the toothed wheel 7, the teeth or pins 9 thereon successively engage and lift the circuit breaker 22 to the dotted line position shown in Fig. 6, each pin after passing the circuit breaker permitting the latter to drop by gravity to its normal lower position, as shown by the full lines in Fig. 6. The lifting of the circuit breaker by each pin causes the arms 23 and 24 of the circuit breaker to disengage from the conducting strips 18 and 19 and to lift clear of the bodies of mercury contained in the wells 16 and 17. Continuity of the circuit between the terminals 20 and 21 is thereby broken each time the circuit breaker is acted on by 130

one of the pins or teeth, and this breaking by the circuit breaker of this instrument and the re-closing of the circuit between the breaks actuates the relay 105, causing the 5 signals or indicators contained in the local circuit thereof to respond to the signal transmitted from the instrument. After the sending of the signal from the instrument has been completed, the normally closed line 10 circuit of the system is restored and any other instrument in the system may be similarly set into operation. In the normal condition of each instrument, there is no ground connection with any of the instruments, as 15 the brush or spring contact 53 of each instrument normally rests on the insulating drum 34. However, upon the releasing of the instrument, the grounding disk 50 of the instrument comes into engagement with the 20 brush or spring contact 53, and a ground connection is then established for the instrument in operation, the ground being completed from the terminal 20 through the circuit breaker 22, the terminal 28, conductor 25 58, binding post 57, conductor 56, the spring contact 53, the disk 50, and the frame of the instrument which is indicated diagrammatically in Fig. 10 as the conductor 108. By moving the switches S and S', which are 30 located at the central or receiving station, to the dotted line positions, the main battery B' will be grounded at one side, and a signal could be obtained from the instrument using the ground as one side or a part of the circuit, thus enabling the instrument to transmit 35 a signal in the event that the line circuit of the system is broken or is undergoing repairs. In such case, the current would pass from the main battery B' over conductor 40 98, switch blade 99, contact 110 and conductor 109 to the ground G, thence from the ground G² of the instrument B over the conductor 108, shaft 35, disk 50, brush or contact 53, conductor 56, binding post 57, conductor 58, terminal 28, the circuit breaker 22, the conducting strip or plate 19, terminal 21, conductor 75, binding post 74, conductor 73, through the terminals 67 and 80 and over the line wire 103 to the terminal 104 of the 50 relay, through the line circuit of the relay 105 to the line terminal 106 thereof, thence over the conductor 107 to the return side of the battery. Such would be the operation if the line circuit were broken at the point X 55 between the instruments A and B and a signal were sent from the instrument B. If the break occurred at the same point as before, but instrument A were set into operation, the current from the main battery B' 60 would pass, as before, to ground G, thence from ground G' to instrument A, thence through the grounding and circuit breaking devices of that instrument to the line wire 100, returning through the wire 111 and the 65 relay 105 to the return side of the battery.

It will be understood that a break in the all-metallic line of the system will be indicated at the central station by a continuous indication of the register 119 and by a continuous sounding of the gong 118, and the 70 attendant will then shift the switches S and S' to their dotted line positions (Fig. 10) pending repair of the line.

While the main line system is grounded, and the switch S' occupies the dotted line 75 position (Fig. 10), the bell and register which are then connected in the local circuit of the relay 123 will respond to the signals or alarms coming over the line in the same manner that these devices respond to such 80 signals when the all-metallic line of the system is unbroken and the bell and register are controlled by the relay 105.

The key or plunger 29 may be used by the fire department official or other attendant as 85 a means for manually sending a special signal or alarm over the system, in which case the circuit controller 22 would be caused to rise and fall manually to break and re-establish the line circuit, the signal being sent 90 over the line in a manner similar to that where the signal is transmitted automatically by operation of the signal wheel 7. The key 29 is also used to send a pre-arranged signal over the line from any instrument or box to the central station to notify 95 the central station operator that it is desired to use a telephone on the line. In using a telephone on the line, the attendant at the box or instrument inserts his telephone plug 100 into the jack 83, thus bridging the terminals of his telephone over the line terminals 67 and 68, and the central station operator inserts the plug of his telephone into the jack J and opens the circuit closer K. 105 The key 29 is then pressed up to render operative the line circuit through the telephone at the instrument by opening the short circuit between the jack terminals and the key is held up while the telephone is in 110 use. When the telephones are to be removed from the system, the pressure upon the key 29 is released, allowing the circuit controller 22 to complete the line circuit, and the telephone plug at the instrument is removed 115 from its jack and the central station operator closes the circuit closer K and then removes the plug of the telephone at the central station from its jack J. The grounding key 97 may also be used to send 120 a special signal over the system from the respective instrument or box, while the switch S is in the dotted line position (Fig. 10), and this key may also be used in testing the system.

By providing a circuit controller having its contacts submerged in baths of mercury, the engaging surfaces of such contacts are, under ordinary conditions, covered and protected from the corroding influences of 130

- gases and other elements which, it has been found, attack the ordinary exposed contacts as heretofore used and thereby render the operation of a system of this character 5 uncertain and hence unreliable. Therefore, certainty and reliability in the operation of the system is insured by providing, at all times, good conductivity between the working or signaling contacts. This result is attained by the present invention and yet operating movement of the working contact is not impeded, as the mercury offers negligible resistance to the movement of the working contact.
- 10 15 By providing a normally closed circuit system which, under ordinary conditions, operates without a ground return to its main battery or source of energy, there is practically no opportunity for damage to or interference with the operation of the system by crossing of its wires with those of other circuits. Furthermore, by connecting the telephone in series in the line circuit of the system, satisfactory use may be made of the 20 25 telephone, as compared with such systems which employ a ground return, for, in such latter systems, interference by other circuits using ground returns impairs or prevents the use of a telephone.
- 30 I claim as my invention:—
1. In an alarm mechanism, circuit breaking means comprising a closed casing, a movable circuit breaking element housed within the closed casing, contacts coöperating with the circuit breaking element, a motor driven actuator housed within the casing for mechanically operating the circuit breaking element, and means operable from the exterior of the casing for manually 35 40 moving the circuit breaking element independently of the before-mentioned actuator.
  2. In an alarm system, circuit breaking means comprising a closed casing, a freely gravitating circuit breaking element in the 45 casing, contacts coöperating with the circuit breaking element, a motor driven actuator

for mechanically operating the circuit breaking element, and normally inoperative manually controlled means for lifting the circuit breaking element independently of 50 the before-mentioned actuator.

3. In an alarm mechanism, circuit breaking means comprising a substantially air tight casing of insulating substance, a freely 55 gravitating circuit breaking element in said casing, a mercury bath within the casing to contact with said breaking element, an axis wholly within the casing and on which the breaker element is lightly pivoted, and a motor driven actuator wholly within the 60 casing and operatively associated with the breaking element.

4. In an alarm mechanism, circuit breaking means comprising a yoke shaped conducting member, an axis on which said member is freely pivoted for gravitation, contact means arranged for coöperation with the sides of said member, and a motor driven 65 70 rotary actuator constructed to engage the portion of the conducting member intermediate its sides to lift and drop the said member a predetermined number of times.

5. In fire alarm mechanism, circuit breaking means comprising a substantially air tight casing of insulating substance, an actuator, a freely gravitating circuit breaker in said casing, a mercury bath in the casing to contact with said breaker, an axis wholly within the casing and on which the breaker is lightly pivoted, said actuator being 75 80 wholly in the casing, means to mechanically operate said actuator, and means operable from a point exterior to the casing for manually operating the breaker.

In testimony whereof I have hereunto set 85 my hand in presence of two subscribing witnesses.

MANIOUS GARL.
